AUTOMATIC SECRETARIAL REMINDER

Joseph A. Albers, Cheviot, Ohio

Application August 5, 1949, Serial No. 108,715

5 Claims. (Cl. 161—6)

1

The present invention relates to improvements in an automatic secretarial reminder which is operated by a time controlled mechanism and has for an object the provision of a device of this kind by which an executive or other office worker is reminded of matters usually called to his attention by his secretary. The device is adapted to be placed upon a desk or the like in an office to be employed to notify the user of business or other appointments, such as, making telephone calls at a predetermined time, or to call attention to any other matter involving an element of time.

Another object of the present invention is to provide an improved structure which can be associated with and operated by a conventional alarm clock, either of the mechanical or the electrical type.

A further object of the present invention is to provide an improved device in which a memorandum card or pad holder can be moved to its retracted set position on the clock by merely actuating a reset lever which simultaneously sets the alarm lever of the clock.

A still further object of the present invention is the provision of an improved structure in which means are incorporated for projecting the memorandum card or pad holder so that a visible as well as an audible signal is given for attracting the attention.

The present invention aims to provide an improved device of this character in which the means for projecting the memorandum card or pad holder is normally held inoperative and is released for projecting the holder by movement of the alarm mechanism of the clock.

The present invention also aims to provide an improved structure which comprises relatively few parts, is simple and economical to manufacture and will not easily get out of order.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of the improved device constructed in accordance with the present invention and showing the memorandum card or pad holder in its projected position.

Figure 2 is a rear elevational view of the device with parts broken away and parts in section and showing the position of the parts when the memorandum holder is in its projected position.

Figure 3 is a horizontal sectional view taken

2

on the line 3—3 of Figure 2 and looking in the direction of the arrows.

Figure 4 is a view similar to Figure 2 but showing the position of the parts when the memorandum holder is in its retracted position.

Figure 5 is a vertical sectional view taken on the line 5—5 of Figure 2 and looking in the direction of the arrows.

Figure 6 is a perspective view of the memorandum card or pad holder.

Figure 7 is a perspective view of the reset lever, and

Figure 8 is a perspective view of the release rod.

Referring more particularly to the drawings, 10 indicates a base of a clock casing, 11 a front wall or panel, 12 a rear wall, 13 and 14 opposite side walls and 15 a top wall. A clock works 16 is mounted within the clock casing and is supported by the front panel 11 to which it is attached by screws or the like 17. The clock works 16 may be of the conventional mechanical or electrical alarm type and has a back plate 18. A conventional dial 19 and hands 20 and 21 of the clock works are visible through a suitable window in the front panel 11 of the clock case and a crystal 22 protects the dial and hands.

A shaft 23 of the alarm mechanism of the clock works 16 projects outwardly through the back plate 18 and a sprocket wheel 24 is fixed to the projecting end portion of the shaft 23. A sprocket chain 25 is trained about the sprocket wheel 24 and a sprocket wheel 26 fixed to a shaft 27 which is rotatably supported by the front panel 11 of the clock case and a bearing pedestal 28. The pedestal 28 is mounted upon the base 10 of the clock case and the rear end portion of the shaft 27 extends through an opening in the pedestal and is peened over to prevent withdrawal. The forward end portion of the shaft

30 27 extends through a suitable opening in the panel 11 and has a knob 29 fixed on its forward extended end portion. A pointer 30 is mounted upon or formed integral with the knob 29 and is adapted to be moved by rotation of the knob 45 around a dial 31 which bears the numerals one to twelve corresponding to the indicia on the dial of the clock works. The shaft 27 extends through an appropriate opening in the dial 31 which is mounted on the outer face of the front panel 11 of the clock case. A conventional alarm lever 32 is mounted on the clock works 16 for setting the alarm mechanism in position to operate when the clock works reaches the time at which the alarm has been set to operate.

50 55 A memorandum card or pad holder generally

indicated at A is mounted for vertical movement through a slot 33 formed in the top 15 of the clock case. The holder A has a base 34 which may be in the form of an elongated plate and has depending from its opposite forward edge portions feet 35 which may be substantially triangular in shape, the outer edge portion 35a of each foot being substantially vertical and extending beyond the end of the base 34. A memorandum card or pad 36 is held by a frame which comprises a bottom 37 and a pair of spaced apart oppositely disposed U-shaped members generally indicated at 38.

The bottom 37 is attached to the upper face of the base 34 and is of substantially the same shape and length as the base but is of less width to provide an upwardly facing shoulder 39. Each member 38 comprises a pair of spaced apart vertically extending legs 40 and a bridge portion 41 connecting the legs 40 to form a channel 42 for the reception of the opposite end portions of the memorandum card or pad. The members 38 are attached to the bottom 37 in any suitable manner. A panel 38a is disposed between and has its opposite ends attached to the free edges of the back legs 40 of the member 38 and its lower edge engaging the upper face of the bottom 37 to support the intermediate portion of the memorandum card or pad. An apertured ring 43 is secured to the under face of the base 34 substantially medially thereof. Each of a pair of spaced apart substantially S-shaped guides 44 have one flange secured to the inner face of the front panel 11 of the clock case adjacent opposite ends of the slot 33 in the top 15 and its other flange is disposed in spaced apart relation to the inner face of the front panel 11 to form a vertically extending guideway 45 for receiving the outer edge portions 35a of the feet 35.

A link 46 has its upper end pivotally connected to the ring 43 of the memorandum holder by a pin or the like 47 and its lower end pivotally connected to the inner end portion of a link 48 by a pin or the like 49. The outer end portion of the link 48 is pivotally mounted on a pin or the like 50 which is supported by a pair of spaced apart brackets 51 attached to the inner face of the side wall 13 of the clock case. A coiled spring 52 encircles the pin 50 and one end portion of the spring bears against the inner face of the side wall 13 of the clock case and its opposite end portion bears against the under beveled surface of a projection 53 which is formed on the link 48 adjacent its outer end.

A substantially vertically extending catch bar 54 is pivotally connected intermediate its ends by a pin or the like 55 to the link 48 inwardly of its projection 53. The upper end portion of the catch bar 54 is pivotally connected to a reset lever 56 by a pin or the like 57. The outer edge of the lower end portion of the catch bar is cut away as at 58 on a downward and inward inclination to form a catch shoulder 59. Intermediate its ends the reset lever 56 has an angularly offset portion 60 so that the inner end portion 61 of the lever 56 is disposed rearwardly of the clock works 16. A cylindrical bearing 62 extends rearwardly from the rear face of the inner end portion 61 of the lever 56 and is rotatably received by a bearing pin 63 which is mounted on the inner face of the rear wall 12 of the clock case. The free end of the pin 63 can be peened over to prevent the lever 56 from escaping therefrom. A substantially triangularly shaped brace

64 is attached to the inner end portion 61 of the lever 56 and to the bearing 62. The outer free end portion of the lever 56 extends outwardly through an opening 65 in the side wall 13 of the clock case and is provided with a finger engaging portion 66 outwardly of the casing.

A release catch 67 in the form of a bell crank lever is pivotally mounted by a pin or the like 68 on a boss 69 which in turn is mounted on the inner face of the front panel 11 of the clock case. The horizontal arm of the bell crank lever extends outwardly through an opening 70 in the side wall 13 of the clock casing and has a finger piece 71 on its outer extended end. The vertical arm of the bell crank lever is cut away as at 72 on an upward and outward inclination to form a shoulder 73 which at times engages the shoulder 59 on the catch bar 54.

A coiled spring 74 has its lower end portion housed by a cup 75 which is mounted on the base 10 of the clock case and its upper end portion encircles a nipple 76 which depends from the lower face of the horizontal arm of the release catch 67. The spring 74 bears against the under surface of the horizontal arm of the release catch 67 at a point disposed outwardly of the pivot 68 so that the vertical arm of the catch 67 will be normally swung inwardly to engage the shoulder 73 with the shoulder 59 of the bar 54.

The upper end portion of the release catch 67 is pivotally connected by a pin or the like 77 to the outer end portion of a release rod 78 which extends inwardly and has an angularly offset portion 79 so that the inner end portion 80 is disposed rearwardly of the clock works 16. The upper edge portion of the release rod 78 is notched as at 81 to accommodate the shaft 21 and the inner end portion 80 of the rod 78 is supported by a guide strap 82 which is mounted on the outer face of the back plate 18 of the clock works by suitable fastening elements 83, such as screws or the like. The inner end of the rod 78 is disposed in the path of rotation of a cam 84 fixed to a shaft 85 which is rotated by the alarm mechanism of the clock.

In the use of the device, let it be assumed that the alarm mechanism shaft 85 has rotated the cam 84 so that the high point 84a of the cam has moved the release rod 78 to the left looking at Figure 2. This movement of the release rod will rock the release catch 67 out of engagement with the catch bar 54 and the holder A will be moved to its projected position shown in Figures 1, 2 and 5 as later described. The alarm mechanism shaft 85 will continue to rotate the cam 84 until the high point 84a of the cam moves out of contact with the end of the release rod 78. The release catch 67 under the influence of its spring 74 and the release rod 78 are moved to the right to the position shown in Figure 4. If the user has an appointment or wishes to make a telephone call at some specific time, for example, at 2 p. m., a memorandum of the appointment or call will be made on a card or pad which will be inserted in the holder A. The knob 20 will be rotated until the pointer 30 registers with the numeral 2 on the dial 31. This movement of the knob 20 will cause the alarm mechanism of the clock works 16 to be set for 2 o'clock through the rotation of the shaft 21, the sprocket wheel 26, sprocket chain 25, sprocket wheel 24 and shaft 23 of the alarm mechanism.

The finger engaging portion 66 of the reset lever 56 will then be depressed and the reset lever will be swung downwardly on the bearing

75

pin 63. This downward movement of the reset lever will move the alarm lever 32 which is disposed in the path of downward movement of the reset lever to its set position so that the alarm mechanism will operate when the clock works 16 reaches 2 o'clock. At the same time, the downward movement of the reset lever 56 will cause the holder A to be retracted to its retracted position illustrated in Figure 4. This retraction of the holder will be effected by the lever 56 moving the catch bar 54 downwardly through the connection 57. As the catch bar 54 is forced downwardly, it will cause the link 48 to swing downwardly about its pivot 50 against the tension of the spring 52 and the link 48 through the pin 49, the link 46 and the pin 47 will draw the holder A downwardly through the slot 33 in the top 15 into the clock casing as shown in Figure 4. The guideways 45 will cause the holder to travel in a straight line and prevent jamming of the holder. As the catch bar 54 moves downwardly the opposed beveled faces 59^a and 73^a of the shoulders 59 and 73 will move the vertical arm of the release catch 67 to the left so that the shoulder 59 will move below the shoulder 73. The spring 74 will move the shoulder 73 into locking engagement with the shoulder 59 to hold the parts in their set position as illustrated in Figure 4.

When the clock works 16 have traveled to 2 o'clock, as indicated by the hands 20 and 21 in Figure 1, the alarm mechanism is actuated. The cam 84 is rotated by the shaft 85 in the direction indicated by the arrow 86 as shown in Figure 2 so that the high point 84^a of the cam engages the inner end of the release rod 78 and shifts the release rod to the left looking at Figure 2. This movement of the release rod 78 rocks the release catch 67 on its pivot 68 to disengage the shoulders 59 and 73. The spring 52 being under tension, as explained above, will force the link 48 upwardly and through the pin 49, link 46 and pin 47 project the holder A suddenly upwardly and out of the slot 33 in the top 15 of the clock casing. This sudden ejection of the holder A will provide a visible signal that will attract the attention of the user of the device and will supplement the conventional audible signal of the alarm mechanism.

The shoulder 39 on the base 34 of the holder A will engage the under face of the top 15 adjacent the slot 33 to limit the upward movement of the holder and the actuating parts therefor. When the reset lever 56 moves upwardly it will free the alarm lever 32 so that the alarm lever will move to shut off the alarm mechanism. If, after the device has been moved to its set position, it is desired to change a memorandum or add another memorandum or the like, the holder A can be projected to permit access to the memorandum card 36 without waiting for the clock works to reach the time for which the device has been set. The operator can depress the finger piece 71 of the release catch 67 with his finger, as illustrated in Figure 2 to permit operation of the parts as described above to project the holder A. The new or amended memorandum can then be written on the card or pad 36 and the device reset by depressing the finger engaging portion 66 of the reset lever 56.

It is obvious that various changes and modifications may be made in the details of construction and design of the above specifically described embodiment of this invention without departing from the spirit thereof, such changes

and modifications being restricted only by the scope of the following claims.

What I claim is:

1. An improved automatic secretarial reminder comprising a clock works having an alarm mechanism, supporting means for the clock works, a memorandum card holder mounted on said supporting means for movement between a set position and an accessible position, a link movably mounted on said supporting means and connected to said holder, resilient means supported by said supporting means for normally urging said holder to its accessible position, a releasable locking mechanism for releasably locking said link and holder in the set position of the holder comprising a catch bar connected to said link and having a shoulder thereon and a bell crank lever movably mounted on said supporting means and having a shoulder thereon for engaging the shoulder on said catch bar when in its locking position, and means actuated by the alarm mechanism for releasing said releasable locking mechanism.
2. An improved device as claimed in claim 1 characterized by the fact that resilient means are provided for urging said bell crank lever into its locking position and that said bell crank lever is provided with a finger piece for permitting manual disengagement of said shoulders.
3. An improved device of the kind described comprising a clock works having an alarm mechanism, supporting means for the clock works, a memorandum pad holder mounted on said supporting means for movement between a set position and an accessible position, a reset lever movably mounted on said supporting means, an alarm setting lever connected to the alarm mechanism and disposed in the path of downward movement of the reset lever, a link movably mounted on said supporting means and pivotally connected to said holder, a catch bar pivotally connected to said reset lever and to said link, resilient means supported by said supporting means for normally urging the link, the reset lever and the holder to the accessible position of said holder, a release catch movably mounted on said supporting means, said release catch and said catch bar having cooperating portions for releasably locking the holder in its set position, resilient means mounted on said supporting means for normally urging the cooperating portions of said catch bar and release catch into locking position, a release rod movably mounted on said clock works and connected to said release catch, and a cam actuated by the alarm mechanism for moving said release rod, whereby said release catch is moved to its inoperative position.
4. An improved automatic secretarial reminder comprising a clock works having an alarm mechanism, supporting means for the clock works, a memorandum pad holder mounted on said supporting means for movement between a set position and an accessible position, means for moving the holder to its set position, releasable means for retaining said holder setting means in its holder setting position, means actuated by the alarm mechanism for releasing said releasable means, said supporting means comprising a casing having a front panel and a top provided with a slot, guide means mounted on the inner face of said front panel adjacent said slot, said holder comprising a base, a pair of feet, portions of which are received by said

guides, a bottom mounted on said base, a pair of upstanding spaced apart legs supported by said bottom and having channels therein for the reception of a memorandum card or the like, and a panel resting upon said bottom and having its opposite ends attached to said legs, said base having a portion for engaging the under face of said top of the casing adjacent said slot when the holder is in its accessible position for limiting the outward movement of the holder with respect to the casing.

5. For use with a clock works having a casing, a dial and an alarm mechanism provided with an alarm setting shaft, an improved automatic secretarial reminder comprising a second dial adapted to be mounted on said casing and having indicia thereon corresponding to the indicia on the dial of the clock works, a shaft adapted to be rotatably supported by said casing, a knob having a pointer and fixed to one end of said shaft for rotation about said second mentioned dial, a sprocket wheel mounted on said shaft, a second sprocket wheel adapted to be mounted on said alarm setting shaft, a sprocket chain trained about said sprocket wheels, a memorandum card holder adapted to be mounted in said casing for

movement between a set retracted position within the casing and an accessible projected position without the casing, means adapted to be mounted on said casing for moving the holder to its set position, releasable means adapted to be mounted on the casing for retaining said holder setting means in its holder setting position, and means adapted to be mounted on the casing and actuated by the alarm mechanism for releasing said releasable means.
